UNITED STATES PATENT OFFICE.

ANKER PETERSEN, OF WINTHROP, MASSACHUSETTS, ASSIGNOR, BY MESNE ASSIGNMENTS, TO THE AMERICAN WIREMOLD COMPANY, OF HARTFORD, CONNECTICUT, A CORPORATION OF CONNECTICUT.

METHOD OF MAKING LACES.

1,380,411.

Specification of Letters Patent. Patented June 7, 1921.

Application filed August 25, 1919. Serial No. 319,788.

To all whom it may concern:

Be it known that I, ANKER PETERSEN, citizen of the United States of America, and resident of Winthrop, in the county of 5 Suffolk and State of Massachusetts, have invented new and useful Improvements in Methods of Making Laces, of which the following is a specification.

This invention relates to a new method or 10 art of making tipped laces for shoes or other eyeleted garments.

Heretofore such laces have been made from solid, flat or tubular braid or woven fabrics of indefinite length, such as cords, 15 tapes or tubes of linen, silk, cotton or other suitable material which is measured off, cut into sections, and each end of each section then provided with a tip. In some cases the tip is a ferrule or wrapping of metal or 20 wire fastened upon the lace by an adhesive or mere friction; or such a ferrule or wrapping is formed by celluloid or other plastic, and attached by cementing or by softening the tip and compressing it in place. Such 25 celluloid or plastic tips are durable and otherwise advantageous, but heretofore, so far as I am aware, have been found to be difficult to attach properly to the end of the lace, so that skilled labor is required, and so 30 that material is wasted and the result is often uncertain. It is difficult to secure the accurate length of lace from tip to tip required by the trade.

The present invention provides a new 35 method of producing tipped laces of accurate length, the material of the lace in the preferred product extending over the outer surface of a solid tip, which has a durable and certain attachment to the lace, the tips 40 being of the same texture and color as the lace, and having other desirable characteristics including cheapness due to avoidance of skill and of any waste of material during making.

45 Explanatory instances of the invention are shown in the accompanying drawings, in which—

Figure 1 is a diagram side elevation of a 50 braiding machine illustrating one preferred step in the manufacture;

Fig. 2 is a diagram elevation illustrating a severing operation;

Fig. 3 is an elevation showing the adjacent tipped ends of two laces;

Fig. 4 is a longitudinal section of the tip 55 of a lace;

Fig. 5 is a diagram section of dies for forming the tip;

Fig. 6 illustrates modified means suitable for feeding tip blanks in the practice of the 60 method; and

Fig. 7 illustrates one form of shear for severing the tipped laces.

The art of making includes applying a 65 blank of material for a tip in accurate spaced relation to a length of fabric, forming two tips at the end of each placed blank, and severing the formed tips apart to separate the completed laces.

Referring to Fig. 1 the usual type of lace 70 comprises a tubular braid 1 formed of yarns 2 braided at the bottom edge of a tubular mandrel 3 of a suitable circular braiding machine, and carried away from the machine as formed in the direction of the arrow *a* by a suitable take-up roll or rolls, not shown. The product is a tubular fabric of indefinite length. If desired, the fabric may be made by weaving or knitting instead of 75 braiding, but braiding is preferred.

In order to carry out one step of the new 80 method, blanks for lace-tips are introduced into the forming fabric at predetermined intervals corresponding to the distance from tip to tip of the desired lace, and are held 85 in place by frictional engagement within the formed tube until a subsequent stage of the manufacture. These blanks may be of any material suitably plastic under pressure or heat or the action of a solvent, such as 90 celluloid, and may be introduced by hand or any suitable means, for instance, as shown in Fig. 1 when the operation is by braiding, rolls 5, suitably driven at a speed conformable to that of the take-up or 95 growth rate of the tube 1, may be operated to move in the direction of arrow *b* a continuous strip 6 of sheet celluloid or other suitable substance, guided in a direction 100 axial of the machine by a guide 7. Motion 100

of the rolls 5 may be either a slow continuous motion, or an intermittent faster motion, in either case timed to insert the end of the strip 6 in the forming braid at the proper distance from the position of a previously inserted tip blank. When the end of the strip 6 is engaged by the braid or other fabric formed about it, the tip blank 8 is severed from the strip 6, for instance by 10 shears 9, and thereafter travels with the braid as pulled off by the take-up rolls.

Another way of introducing the tip blanks at the proper distances apart is shown in Fig. 6, the tip blanks 8 in this 15 case being attached at the proper distances to a core-cord 10 by any convenient means, as by sticking the cord to the blanks with an adhesive, by stringing the cord 10 through punctures in the blanks, or otherwise. The 20 core-cord is engaged within the braid and taken away in direction *a* by the take-up, and so introduces the blanks 8 successively at the proper intervals.

The string of fabric 1 is now treated to 25 mold the tips and attach them within the tubular braid of which it is composed. The draft of the yarns 2 will have rolled or curled thin flat blanks 8 somewhat, and these tip blanks and the fabric over them may 30 readily be consolidated together and formed into solid tip-sections 8^a, Fig. 2, by compression, and if desired, the application of heat, for instance, in a suitable mold comprising a fixed die 11 and a movable compressing 35 die 12. If desired the part of the string 1 containing the blank 8 may be moistened with a solvent for the material of the tip, or a fusible adhesive in solution, before treatment by the preferably heated dies 11 40 and 12. The action of the dies 11 and 12 is such as to further curl the blanks into a compact coil as clearly indicated in Fig. 5. This action tends to pinch the fabric whereby to securely hold the blanks in position 45 relatively thereto and when a solvent is used, as above indicated, before treatment by the dies, the pressure exerted by the latter serves to squeeze the dissolved portion of the plastic material into the interstices 50 of the fabric, the sheet form of the blank being acted upon much more readily by a solvent than would a solid rod of material be under the same circumstances. The ultimate result of the action of the dies together 55 with the solvent, is to produce a solid tip of substantially cylindrical form and in which the parts are so intimately united as to preclude any possibility of separation in use.

To complete the separate laces each having a tip 8^b Figs. 3 and 4 the tips section 8^a is sheared through preferably while still warm or plastic from the previous treatment, the result being to cover over the sheared end of the tip with and thoroughly

to embed the cut edge of the fabric 1 in 65 the material of the tip as shown at 8^c. If desired, the tip ends may be additionally formed and pointed, as by severing them by notched shears 15, Figs. 2 and 7, or by pushing by hand into a conical forming die 70 after severing by any kind of knife or shears.

While for purposes of illustration the making of a tubular fabric with inserted blanks 8 has been described above, it will 75 be understood without further description by skilled weavers, knitters or braiders that the fabric may be tubular only at the place of insertion of the blank, and flat or solid elsewhere. 80

The consolidated tip in any case is immovably fastened to and within the fabric and at an accurate distance from the other tip defining the length of lace, is inconspicuous and an effective penetrator of eyelet-holes. 85 The tip blanks may be of transparent or any desired color of material to match the color of the lace 1.

What I claim is:

1. The art of making tipped laces comprising forming a fabric, inserting therein at predetermined intervals blanks of sheet material for tips, and subsequently completing the laces by consolidating the sheet material and the surrounding fabric by compression whereby to coil said material upon itself and embed the fabric therein and severing the lace from the length of fabric. 90

2. The art of making tipped laces comprising forming a fabric, inserting therein at predetermined intervals blanks of sheet material for tips, and subsequently completing the laces by consolidating and shaping the material and the surrounding fabric by compression in a forming die whereby 100 the sheet material is caused to coil upon itself and severing the lace from the length of fabric. 105

3. The art of making tipped laces comprising forming a tubular fabric having 110 therein at spaced intervals blanks of plastic sheet material and subsequently subjecting the fabric and the inclosed blank to heat and pressure at the places of the blank whereby to coil said blank upon itself to form a tip 115 section.

4. The art of making tipped articles of textile fabric which comprises making a tubular fabric of component yarns by weaving, braiding or knitting, feeding into the 120 forming fabric a blank of sheet material, causing said blank to receive an initial transverse curl by engagement with the yarns adjacent the fabric forming point, and subsequently subjecting the fabric at the place 125 of the blank to pressure to complete the curling of the blank upon itself.

5. The art of making tipped articles of

textile fabric which comprises making a tubular fabric by braiding or the like, feeding into the forming fabric a strip of plastic sheet material, moistening said fabric, after its formation, at the place of the inclosed

5 strip with a solvent for the material of the

strip, and subjecting the fabric at the place of the strip to pressure whereby to coil said strip upon itself.

Signed by me at Boston, Massachusetts, 10
this 13th day of August, 1919.

ANKER PETERSEN.
